UNITED STATES PATENT OFFICE.

PETER BLATT, OF ALLEGHENY, PENNSYLVANIA.

JOINT FOR CURTAIN-STRETCHERS, STEP-LADDERS, OR THE LIKE.

SPECIFICATION forming part of Letters Patent No. 684,597, dated October 15, 1901.

Application filed July 8, 1901. Serial No. 67,563. (No model.)

To all whom it may concern:

Be it known that I, PETER BLATT, a citizen of the United States of America, residing at Allegheny, in the county of Allegheny and State 5 of Pennsylvania, have invented certain new and useful Improvements in Joints for Curtain-Stretchers, Step-Ladders, or the Like, of which the following is a specification, reference being had therein to the accompanying 10 drawings.

This invention relates to certain new and useful improvements in joints or hinged and rigid connections, such as are used for folding curtain-stretchers, folding step-ladders, 15 collapsible crates, and the like.

The present invention has for its object the provision of novel means whereby two sections are rigidly secured together and may then be operated in such a manner as will admit 20 the two sections to be easily folded upon one another.

Another object of my invention is to construct a device of the above-described character that will be extremely simple in construction, 25 strong, durable, and comparatively inexpensive to manufacture, and highly efficient in its operation.

With the above and other objects in view the invention consists in the novel combination and arrangement of parts to be herein-after more fully described, and specifically 30 pointed out in the claims.

In describing the invention in detail reference is had to the accompanying drawings, 35 forming a part of this specification, and wherein like numerals of reference indicate corresponding parts throughout the several views, in which—

Figure 1 is a plan view of two sections connected together by my improved joint. Fig. 40 2 is a similar view showing the same folded. Fig. 3 is a side elevation of Fig. 1. Fig. 4 is a perspective view of the locking-bolt.

In the drawings the reference-numerals 1 45 and 2 represent two sections of a frame, ladder, or the like, each of these sections having formed at their meeting ends square notches 3 3. These notches when the sections are folded together will register with one another 50 and form a square opening.

The reference-numeral 4 represents a metallic strap or strip of wood, as the case may

be, and a corresponding strap 5 is arranged upon the opposite side of the joint. The strap 4 has formed therein a central aperture 55 6 and apertures 7 7, and the strap 5 is provided with a central square opening 8 and end apertures 9 9, said apertures corresponding with the apertures 7 7.

The reference-numerals 10 10 represent 60 screw-threaded bolts passing through the straps 4 and 5 and through apertures 9 9 and 7 7, the ends of the threaded bolts being adapted to receive thumb-nuts 11 11.

The reference-numeral 12 indicates a locking-bolt having a square body portion 14 and head 15 and a screw-threaded shank 16. This locking-bolt is inserted in the central openings of the straps 4 and 5, the head portion 15 resting against the strap 5 and the square 70 body portion being seated in the square opening formed by the notches 3 3, the screw-threaded shank extending through the central opening 6 of the strap 4 to receive the thumb-nut 17. 75

The manner of operating my improved joint is as follows: When it is desired to fold a curtain-stretcher, collapse a ladder, or fold a crate, the thumb-nut 17 is removed and the locking-bolt is likewise removed from the 80 joint, thus admitting the two sections to be folded in a manner as shown in Fig. 2 of the drawings, and when it is desired to again place the parts in their former position the sections are placed in position as shown in 85 Figs. 1 and 3 of the drawings and the locking-bolt then inserted, as hereinbefore described.

The many advantages obtained by the use of my improved device will be readily apparent from the foregoing description, taken in 90 connection with the accompanying drawings.

It will be noted that various changes may be made in the details of construction without departing from the general spirit of my invention.

Having fully described my invention, what I claim as new, and desire to secure by Letters Patent, is—

1. In a joint, the combination of two sections having formed in their meeting ends 100 square notches, a strap pivotally connected to said sections, and a locking-bolt extending through said strap and seated in said notches, substantially as described.

2. In a joint, the combination of two sections, a strap arranged on each side of said sections, said sections having formed at their meeting ends square openings, a locking-bolt 5 engaged in said square openings extending through said straps, and means whereby said locking-bolt is rigidly retained in position, substantially as described.

3. In a joint of the character described, the 10 combination of two hinged sections having formed therein square notches at their meeting ends, straps arranged on each side of said sections, screw-threaded bolts extending

through said sections, thumb-nuts arranged upon said bolts, a locking-bolt arranged in 15 the square notches formed in the meeting ends of said sections, and a thumb-nut secured upon said locking-bolt, all parts being arranged and operating substantially as and for the purpose described. 25

In testimony whereof I affix my signature in the presence of two witnesses.

PETER BLATT.
